ROPE SUSPENDED ASCENDING AND DESCENDING SUPPORTING DEVICE

Joseph Niemiec, Irvington, N. J.

Application September 11, 1946, Serial No. 696,265

6 Claims. (Cl. 254—167)

1

This invention relates to an improved rope suspended means for supporting a workman or other used at selected elevated positions, as e. g. relative to a perpendicular wall surface, including means, operable by the user, to cause the supporting device to ascend or descend the suspending rope at will.

The invention has for an object to provide a novel supporting device for the purposes stated which is engaged upon a suspending rope in such manner as to be capable of moving up and down upon said rope; said device being provided with means engaged in tractional relation to the suspending rope; and said device being further provided with means, operable by the user of the device, for imparting motion to the tractional means whereby to cause the device to ascend or descend the suspending rope at will.

The invention has for another object to provide, in a device of the kind stated, a releasable safety clutch means adapted to engage the suspending rope so as to positively prevent accidental descent of the device along said rope.

Other objects of this invention, not at this time more particularly enumerated, will be understood from the following detailed description of the same.

An illustrative embodiment of this invention is shown in the accompanying drawings, in which:

Fig. 1 is a side elevational view of a rope suspended ascending and descending supporting device according to this invention; Fig. 2 is a vertical longitudinal sectional view, taken on line 2—2 in Fig. 1, and drawn on an enlarged scale; Fig. 3 is a transverse vertical longitudinal sectional view, taken on line 3—3 in Fig. 2, but drawn on a further enlarged scale; and Fig. 4 is a fragmentary horizontal sectional view through the safety clutch of the supporting device, taken on line 4—4 in Fig. 2, and drawn on an enlarged scale.

Similar characters of reference are employed in the above described views, to indicate corresponding parts.

Referring to the drawings, the reference character 10 indicates a rope by which the movable supporting device is suspended at the desired place of use; the upper end of said rope being secured to suitable anchorage means (not shown).

The supporting device per se comprises a suitably chambered casing 11 adapted to form a carriage through which the suspending rope 10 extends, and in which the means for tractionally engaging said suspending rope is housed. Journaled in and across the casing 11 is a main rotat-

able shaft 12 upon which is fixed a peripherally grooved traction pulley or wheel 13 adapted to engage the upper stretch of the rope 10. Also fixed upon said shaft 13, adjacent to said pulley or wheel 13, is a similarly peripherally grooved traction pulley or wheel 14 adapted to engage the lower stretch of the rope 10. Opposed to an upper portion of the traction pulley or wheel 13 is an intermediate peripherally grooved traction wheel or pulley 15, which is rotatably supported on a stud shaft 16 that is suitably affixed to the casing 11. Similarly, opposed to a lower portion of the traction pulley or wheel 14 is a second intermediate peripherally grooved traction pulley or wheel 17 which is also rotatably supported on a stud shaft 18 that is suitably affixed to the casing 11.

The upper stretch of the suspending rope 10, which enters the upper end of the casing 11 through a top opening 19, is led to the traction pulley or wheel 13 so as to pass around the underside thereof, and thence to and over the first intermediate traction pulley or wheel 15. From said intermediate traction pulley or wheel 15, the rope 10 passes to and around the underside of the second intermediate traction pulley or wheel 17, and thence to and over the traction pulley or wheel 14, from which the lower stretch of said rope 10 depends to pass downwardly out of the casing 11 through a bottom opening 20. By this arrangement of the suspending rope 10, the same is strongly snubbed around the several traction pulleys or wheels in such manner as to establish a very efficient frictional and tractional engagement of said traction pulleys or wheels with the rope, so that, when the traction pulleys or wheels are rotated, the same will grip the rope, whereby to tractionally roll thereon, and thus effect up or down movement of the casing 11 along the rope, as the case may be.

Preferably, the traction pulleys or wheels are arranged in intergeared relation, so that all are positively driven by rotation of the main shaft 12. This may be arranged in any suitable manner, such e. g. as by providing peripheral portions of the traction pulleys or wheels with gear teeth 21, so that the traction pulley or wheel 13 meshes with the traction pulley or wheel 15 in driving relation thereto, and so that the traction pulley or wheel 14 meshes with the traction pulley or wheel 17 in driving relation thereto.

Means, operable by the user of the device, is provided for rotating the main shaft 12 so as to in turn rotate the rope-engaging traction pulleys or wheels. One illustrative form of power trans-

mission means adapted for this purpose, as shown, comprises a suitably located lay or countershaft 22 which is journaled in and across the casing 11 parallel to the main shaft 12. Fixed on said main shaft 12 is a driven gear wheel 23. Fixed on said lay or countershaft 22 is a drive pinion or gear 24 which meshes with the driven gear 23; the ratio of the drive pinion or gear 24 to the driven gear 23 is such as to effect gain in power application to said main shaft 12. Journaled in a suitably disposed bearing means 25, with which the casing 11 is provided, is a drive shaft 26, one end portion of which is disposed to project exteriorly of said casing 11, and upon which exterior end portion of said drive shaft is affixed a crank-handle 27 for imparting motion to said drive shaft. Fixed on the inner end portion of said drive shaft 26 is a beveled driving gear 28 which meshes with and drives a beveled driven gear 29 which is fixed on the lay or countershaft 22, whereby the power of the drive shaft 26 is transmitted to the lay or countershaft, and thence through the gearing 24—23 to the main shaft 12, and said rope engaging traction pulleys or wheels which are driven by the latter.

Suitably affixed to and supported within the interior of the casing 11 above the traction pulley or wheel 13, so as to engage the upper stretch of the suspending rope 10 which extends to the latter, is a releasable safety clutch means. This clutch means, in a preferred form thereof as shown, comprises a housing 30 having a longitudinal way 31 extending perpendicularly therethrough, and through which said upper stretch of the suspending rope 10 extends. Longitudinally movable within said way 31 is a pair of upwardly tapered opposed clutch wedges 32, between which the upper stretch of the suspending rope passes, so that opposite sides of the latter are engageable thereby. The inner faces of said clutch wedges are preferably channeled or grooved conformably to the contours of the rope sides, and said faces may be and preferably are suitably roughened so as to bind the rope in the embrace of the clutch wedges with a strong frictional and non-slipping grip, when disposed in holding engagement therewith. The inclined outer faces 33 of said clutch wedges 32 are slidably supported or backed by the housing 30, preferably by anti-friction rollers 34 with which the latter is provided, so that resistance to longitudinal movements thereof is reduced to a minimum. Said clutch wedges 32 are yieldably upwardly thrust longitudinally to normal rope gripping position by spring means. Said spring means preferably comprises a compression spring 35 which bears against the lower ends of said clutch wedges, and which is supported by a perforate footing plate 36 carried by hangers 37 which are dependent from the lower end of the housing 30. The upper extremities of said clutch wedges 32 freely project exteriorly upward from the upper end of the housing 30.

Means, operable by the user of the device, is provided for moving the clutch wedges to and holding the same in released relation to the suspending rope 10. An illustrative form of such means, as shown, comprises a clutch releasing lever 38 which is pivotally supported adjacent to the upper end portion of the housing 30, preferably by a carrying bracket 39 with which the latter is provided. The forward arm 40 of said clutch releasing lever 38 is preferably bifurcated to straddle the rope 10, and so as to be engageable with the exteriorly projecting upper ex-

tremities of the clutch wedges 32. Suitably supported below the rearward arm 41 of said clutch releasing lever 38 is a rock-shaft 42. Preferably the inner end portion of said rock-shaft 42 is journaled in said carrying bracket 39. The outer end portion of said rock-shaft 42 is journaled in bearing means 43 with which the casing is provided, and so as to project exteriorly from the latter. Fixed on the inner end portion of the rock-shaft 42 is an actuating cam 44 which is movable by said rock-shaft into and out of operative engagement with the rearward arm 41 of said clutch releasing lever 38. Fixed on the exterior end portion of said rock-shaft 42 is a hand lever 45, by which said shaft and the actuating cam 44 thereon may be operated. Means additional to the above described safety clutch means may be provided for further assuring against accidental descent of the supporting device along the suspending rope, said additional means being so arranged as to be also controlled by the clutch releasing lever 38. Said additional means comprises a ratchet wheel 46 which is fixed on the lay or countershaft 22. Cooperative with said ratchet wheel 46 is a pivoted check pawl 47, which is linked by a lost motion link 48 to the rearward arm 41 of the clutch releasing lever 38. When said check pawl 47 is operatively related to the ratchet wheel 46, the latter is permitted to turn, un-checked by the pawl 47, in a direction adapted to permit transmission of motion to the traction pulleys or wheels whereby to rotate the latter in direction to cause upward travel of the supporting device along the suspending rope 10, while the check pawl 47 remains operative to engage the ratchet wheel teeth so as to restrain opposite rotation of the traction pulleys or wheels, and consequently thus prevent downward travel of the supporting device along said suspending rope.

Suitably affixed to the top end of the casing 11 is a seating platform 49 upon which the user of the device may rest. Affixed to and extending upwardly from the top of the casing and its seating platform is a tubular standard 50, the bore of which is aligned with the rope admission opening 19, and thus serves as a guide for the upper stretch of the suspending rope 10.

The user of the device may desire to stand upright upon the device, if such position is more convenient for the pursuit of work to be performed. To facilitate use of the device in such manner, and to render such position safe for the user, the standard 50 is provided with oppositely extending cross arms 51, preferably provided with attachment loops or eyes 52 to which a safety belt (not shown) worn by the user may be secured. To facilitate operation of the device by the user, when the latter occupies a standing position thereon, auxiliary means for applying operating power to the mechanism is provided. This means comprises a crank handle 53, which is rotatably supported at the end of one of said cross arms 51, and which is adapted to drive a sprocket and chain transmission 54 for rotating the drive shaft 26.

The lower stretch of the suspending rope 10 is preferably kept taught by the attachment to its free end of a weight 55 (see Fig. 1). To guard against displacement of the suspending rope 10 from the traction pulleys or wheels 13 and 14, an idler guard roller 56 may be opposed thereto.

In the use and operation of the novel rope suspended ascending and descending supporting

device, the user either seats himself or stands on the supporting platform 49.

When it is desired to ascend the suspending rope, the clutch releasing lever 38 is disposed in the released position shown in Fig. 2, thus permitting the clutch wedges 32 to be urged upwardly into gripping relation to the suspending rope 10 by the spring 35, while at the same time the check pawl 47 is free to operatively engage the ratchet wheel 46. The user may now turn either the crank handle 27 or 53 in clockwise direction, thereby, through the intermediate transmission mechanism, rotating the main shaft 12 in counter clockwise direction whereby to cause the traction pulleys or wheels to move upwardly along the suspending rope 10, and thus cause the supporting device, and the user carried thereby, to ascend said rope. During such ascending movement of the supporting device, the clutch wedges 32 tend to slide downward in the housing under the downward drag of the suspending rope 10 and against the tension of the spring 35, thus relaxing the hold of said clutch wedges upon the rope, so that the latter is unimpeded as to its downward movement through the supporting device, and consequently said clutch wedges offer no substantial resistance to the ascending movement of said supporting device along the rope. Since, under these circumstances, the check-pawl 47 is operatively related to the ratchet wheel 46, it will, by engagement with the teeth of the latter, obstruct any reverse movement of the traction pulleys or wheels and transmission mechanism, whereby, as a safety factor, to prevent any downward movement of the supporting device relative to the suspending rope 10.

When a desired elevation of the supporting device and the user carried thereby is attained, and upward movement of the supporting device ceases, the clutch wedges 32 will be urged by the spring 35 into gripping relation to the suspending rope 10, which grip is enhanced by the upward drag of the rope upon the clutch wedges, and consequently the supporting device and the user carried thereby will be safely sustained against accidental descent along the suspending rope, as will be obvious.

When it is desired to descend the suspending rope 10, the user of the device swings the hand lever 45 to rotate the rock-shaft 42 in direction to upswing the actuating cam 44 with uplifting effect against the rearward arm 41 of the clutch releasing lever 38, thus swinging the latter about its pivot so as to downswing its forward arm 40 against the upper ends of the clutch wedges 32, whereby to depress the latter against the tension of the spring 35, and thus relax the grip of the same upon the suspending rope 10. At the same time, the upswinging movement of the rearward arm 41 of the clutch releasing lever 38 is transmitted through the link 48 to the clutch-pawl 47, whereby to upswing the latter out of operative relation to the ratchet wheel 46. Under these circumstances, the user may turn either crank handle 27 or 53 in counter clockwise direction, whereby, through the intermediate transmission mechanism, to rotate the main shaft 12 in clockwise direction, so as to cause the traction pulleys or wheels to move downwardly along the suspending rope 10, and thereby cause the supporting device and the user carried thereby to descend the latter.

From the above description it will be apparent that the instant invention provides a very ef-

ficient, easily controlled, and exceedingly safe rope suspended supporting device which is adapted to be operated by the occupying user to ascend and descend the suspending rope at will.

5 The device is well adapted for many uses, and especially for use by house and ship painters and other artisans for the support and movement relative to perpendicular walls or like surfaces upon which work is to be performed.

10 I am aware that various changes could be made in the above-described constructions and arrangement of parts, and that widely different embodiments of this invention could be made without departing from the scope of this invention as defined by the herefollowing claims. It is therefore intended that all matter contained in the foregoing description and shown in the accompanying drawings shall be interpreted as illustrative and not in a limiting sense.

20 I claim:

1. A supporting device of the kind described comprising a suspended rope, a carriage through which said rope extends, a main shaft journaled in said carriage, a traction pulley fixed on said 25 main shaft and adapted to be engaged by the upper stretch of said rope, a second traction pulley also fixed on said main shaft and adapted to be engaged by the lower stretch of said rope, intermediate traction pulleys over which the rope runs from said first to said second traction pulley, a countershaft also journaled in said carriage, transmission gearing between said main shaft and countershaft, means operable to drive said countershaft including crank handle means 30 exteriorly of the carriage, a ratchet wheel fixed on said countershaft, a check-pawl cooperative with said ratchet wheel whereby to prevent operation of said countershaft and main shaft in carriage lowering direction, a clutch comprising a pair of clutch wedges adapted to straddle said upper stretch of the rope above said first traction pulley, means to support said clutch wedges, spring means to urge said clutch wedges to rope engaging position whereby under relative upward drag of the rope, the same will grip said rope and thereby hold the carriage against accidental descent therealong, a pivoted clutch releasing lever, a rotatable cam for actuating said 35 level, manipulatable means operable to engage and disengage said cam with said lever, and means interconnecting said check-pawl with said clutch releasing lever whereby operative movement of the latter simultaneously releases the former from operative relation to said ratchet wheel.

40 2. A supporting device of the kind described as defined in claim 1 wherein said first mentioned traction pulley is intergeared with the intermediate traction pulley to which the rope runs therefrom, and said second traction pulley is intergeared with the intermediate traction pulley from which the rope runs thereto.

45 3. A supporting device of the kind described comprising a suspended rope, a carriage through which said rope extends, traction means mounted in connection with said carriage around which said rope passes, power transmission means also mounted in connection with said carriage operable to rotate said traction means to cause the same to move up or down along said rope with carriage propelling effect, said power transmission means including a ratchet wheel, a check-pawl cooperative with said ratchet wheel to normally prevent operation of the transmission 50 means in carriage lowering direction, a clutch

55 75

comprising opposed clutch wedges adapted to straddle the stretch of rope which extends upwardly from said traction means, means to support said clutch wedges, spring means to urge said clutch wedges into gripping relation to said rope under relative upward drag of the latter, whereby to normally hold the carriage against accidental descent along said rope, a pivoted lever operable to release said clutch wedges from gripping relation to the rope, manipulatable means for operating said clutch releasing lever, and means interconnecting said check-pawl with said clutch releasing lever, whereby operative movement of the latter simultaneously releases the former from its restraint upon said ratchet wheel so as to permit operation of said power transmission means in carriage lowering direction.

4. A supporting device of the kind described comprising a suspended rope, a carriage through which said rope extends, a main shaft journaled in said carriage, a traction pulley having peripheral gear teeth fixed on said main shaft adapted to be engaged by the upper stretch of said rope, a second traction pulley having peripheral gear teeth also fixed on said main shaft adapted to be engaged by the lower stretch of said rope, an idler pulley having peripheral gear teeth opposed to said first mentioned traction pulley with its gear teeth in mesh with the gear teeth of the latter, a second idler pulley having peripheral gear teeth opposed to said second traction pulley with its gear teeth in mesh with the gear teeth of the said second traction pulley, the rope being disposed to run from said first traction pulley to said second traction pulley over said first and second idler pulleys, power transmission means mounted in connection with said carriage operable to drive said main shaft and said traction pulleys, said transmission means including a ratchet wheel, a check-pawl cooperative with said ratchet wheel to normally prevent operation of the transmission means in carriage lowering direction, and means to release said check-pawl to permit operation of the transmission means in carriage lowering direction.

5. A supporting device of the kind described comprising a suspended rope, a carriage through which said rope extends, a main shaft journaled in said carriage, a traction pulley having peripheral gear teeth fixed on said main shaft adapted to be engaged by the upper stretch of said rope, a second traction pulley having peripheral gear teeth also fixed on said main shaft adapted to be engaged by the lower stretch of said rope, an idler pulley having peripheral gear teeth opposed to said first mentioned traction pulley with its gear teeth in mesh with the gear teeth of the latter, a second idler pulley having peripheral gear teeth opposed to said second traction pulley with its gear teeth in mesh with the gear teeth of the said second traction pulley, the rope being disposed to run from said first traction pulley to said second traction pulley over said first and second idler pulleys, power transmission means mounted in connection with said carriage operable to drive said main shaft and said traction pulleys, said transmission means including a ratchet wheel, a check-pawl cooperative with said ratchet wheel to normally prevent operation of the transmission means in carriage lowering direction, and means to release said check-pawl to normally prevent operation of the transmission

means in carriage lowering direction, a rope gripping clutch adapted to engage the upper stretch of rope, said clutch being operative to grip the rope under relative upward drag thereof, whereby to normally hold the carriage against accidental descent along the rope, manipulatable clutch releasing means, and means interconnecting said clutch-pawl with said clutch releasing means, whereby operative movement of the latter simultaneously releases the former from its restraint upon said ratchet wheel so as to permit operation of the transmission means in carriage lowering direction.

6. A supporting device of the kind described comprising a suspended rope, a carriage through which said rope extends, a main shaft journaled in said carriage, a traction pulley having peripheral gear teeth fixed on said main shaft adapted to be engaged by the upper stretch of said rope, a second traction pulley having peripheral gear teeth also fixed on said main shaft adapted to be engaged by the lower stretch of said rope, an idler pulley having peripheral gear teeth opposed to said first mentioned traction pulley with its gear teeth in mesh with the gear teeth of the latter, a second idler pulley having peripheral gear teeth opposed to said second traction pulley with its gear teeth in mesh with the gear teeth of the said second traction pulley, the rope being disposed to run from said first traction pulley to said second traction pulley over said first and second idler pulleys, power transmission means mounted in connection with said carriage operable to drive said main shaft and said traction pulleys, said transmission means including a ratchet wheel, a check-pawl cooperative with said ratchet wheel to normally prevent operation of the transmission means in carriage lowering direction, a clutch comprising opposed clutch wedges adapted to straddle the upper stretch of rope, means to support said clutch wedges, spring means to urge said clutch wedges into gripping relation to the rope under relative upward drag of the latter, whereby to normally hold the carriage against accidental descent along the rope, a pivoted lever operable to release said clutch wedges from gripping relation to the rope, manipulatable means for operating said clutch releasing lever, and means interconnecting said check-pawl with said clutch releasing lever, whereby operative movement of the latter simultaneously releases the former from its restraint upon said ratchet wheel so as to permit operation of said power transmission means in carriage lowering direction.
